CHASSIS ENGAGING DEVICE FOR
VEHICLE LIFTSGeorge Frey, Philadelphia, Pa., assignor to Globe
Hoist Company, Des Moines, Iowa, a corpora-
tion of Iowa

Application March 19, 1947, Serial No. 735,582

3 Claims. (Cl. 254—89)

1

This invention relates generally to vehicle lifts and in particular to a device adapted to be carried on a lift frame structure and including a chassis-engaging member which is movable longitudinally and transversely of said frame structure to an adjusted position.

In the servicing of a passenger bus or the like, the lifting of the bus by engaging its axles often times results in parts of the lift being so arranged as to interfere with a complete and free accessibility of a service man to all of the running gears and apparatus underneath the bus. To overcome this difficulty many buses are now provided with lift pads or sockets which are usually carried in pairs at opposite ends of the bus frame or chassis. By lifting on the pads the axles are entirely open so that substantially all of the operating parts underneath the bus are able to be removed or worked on for servicing and replacement purposes. However, since various types of buses differ somewhat in their size and construction, and the arrangement of running gears on their undersides, the lift pads are not uniformly mounted, namely, the pads are carried at varying positions both transversely and vertically of the bus chassis.

It is an object of this invention, therefore, to provide a chassis-engaging device which is adjustably movable to accommodate the lift pads on any type bus.

A further object of this invention is to provide an improved vehicle lift.

Another object of this invention is to provide a pad-engaging device for a lift which is adjustable longitudinally and transversely of the lift, capable of holding a vehicle against tilting movement, and readily removable from the lift at all positions thereof, so as to eliminate any obstructions above the floor level when the lift is lowered.

A feature of this invention is found in the provision of a chassis-engaging device for a lift in which a base member is slidable longitudinally of the lift frame structure and carries an upright bearing for rotatably supporting a horizontal arm adjacent one of its ends. An upright member on the other end of the arm is adapted to be received within a lift pad or socket on a vehicle chassis. By virtue of the slidable support of the base on the lift frame structure, and rotatable movement of the arm through three hundred and sixty degrees, the upright member is completely adjustable longitudinally and transversely of the frame structure to provide for its movement to a pad-engaging position.

Further objects, features and advantages of

2

this invention will become apparent from the following description when taken in connection with the accompanying drawings, in which:

Fig. 1 is a fragmentary perspective view of the front lift of a two-post vehicle hoist showing the assembly therewith of the chassis engaging device of this invention, and the support on the device of a bus chassis.

Fig. 2 is a perspective view of the lift and chassis-engaging device assembly in Fig. 1 in lowered position; and

Fig. 3 is a sectional view taken along the line 3—3 in Fig. 2.

With reference to the drawings, the chassis-engaging devices of this invention, indicated generally as 10, are illustrated in assembly relation with the front lift of a two-post bus hoist. It is to be understood that similar devices 10 may be assembled in a like manner with the rear lift of the hoist.

The front lift is shown in the drawings as including a lift piston 11, operated in a usual manner, and provided with a head structure or saddle member 12 (Figs. 1 and 2) having a pair of oppositely arranged longitudinally extended frame members 13 of an I-beam construction. A pit opening 14 (Fig. 2), formed in the floor 16, is of a substantially H-shape and of a size adapted to receive the head structure 12 and frame members 13 at positions level with the floor when the lift is in its lowered position. The rear ends 17 of the frame members 13, at a lowered position of the lift, are spaced forwardly from the rear ends 18 of the H-shaped pit opening 14, for a purpose which will appear later.

Since the chassis-engaging devices 10 are of a like construction and similarly assembled with a frame member 13, only one of such devices will be referred to in detail in the following description.

A device 10 (Figs. 2 and 3), includes a flat body or base member 19, of a substantially rectangular shape, formed in its bottom side with a pair of oppositely arranged guide ways 21 adapted to slidably receive therein the outer edges 22 of the upper web 23 of the I-beam or frame member 13. A supporting pin 24 (Fig. 3), integrally formed with a head member 26, has its lower end 50 extended within an opening 27, formed substantially centrally of the base member 19, to a position such that the lower edge thereof is substantially flush with the upper ends of the guide ways 21. The pin 24 is rigidly fixed to the base member 19 by securing its lower end with the

base 19 at the opening 27 by welding or like means.

Rotatably supported at one end on the pin 24, and mounted thereon between the head member 26 and the top side of the base member 19, is an arm member 28 integrally formed at its free end with an upright projection or bearing support 29 of a cylindrical shape. The arm 10 is rotatable through a distance of three hundred and sixty degrees in a plane parallel with the plane of the base 19. An upright adapter plug 31 is integrally formed at its lower end with an annular cavity or socket 32 adapted to receive the upright bearing support 29 such that the top end of the support 29 is in bearing engagement with the bottom 33 of the socket 32.

In the operation of the lift, a bus is driven thereover when the lift is in its lowered position shown in Fig. 2. The base members 19 are then moved longitudinally of the frame members 13, concurrently with a rotation of the arms 28, to locate the adapters 31 at positions providing for their reception within lift pads 34 carried in a transversely spaced relation at the front end of the bus chassis or frame 35 (Fig. 1).

The lift pads 34 (Fig. 1) are of a usual construction and of a generally inverted box shape so as to constitute sockets or cavities within which the adapters 31 are loosely extended for bearing engagement with the top side of the pads and held against movement out of engagement with the pads by the pad side walls 36.

It is seen, therefore, that the adapters 31 are adjustable longitudinally and transversely of the frame members 13, by virtue of the slideable movement of the base members 19 longitudinally of the frame members 13, and the rotation of the arm members 28 through an angular distance of three hundred and sixty degrees, so that the adapters 31 are positionable to either side of the frame members 13.

The adapters 31 may be of varying lengths to accommodate various chassis constructions, and the assembly of the pads 34 on the chassis at varying distances vertically on the bus chassis. By virtue of the assembly of the adapters 31 in the devices 10, by merely placing the sockets 32 over the upright supports 29, the substitution of different length adapters 31 for adaptation to varying bus constructions is readily accomplished.

Further, by reason of the reception of the adapters 31 within the side walls 36 of the pads 34, the bus is positively locked against tilting or sliding movement off from a supported position on the lift.

On lowering of the lift, and driving of the bus off therefrom, the devices 10 are removed from the lift by sliding them rearwardly out of supported positions on the frame members 13. This removal is provided by the spaced relation of the rear ends 17 of the members 13 with the rear ends 18 of the pit opening 14. Conversely the devices 10 may be assembled with the frame members 13, at a lowered position of the lift, or at any elevated position of the lift. As a result, of this simple and ready removal of the devices 10 from the frame members 13, the lift when lowered may be maintained entirely free of any upright obstruction, so that all parts thereof are at a substantially floor level position.

Although the invention has been described with respect to a preferred embodiment thereof, it is to be understood that it is not to be so limited since

changes and modifications can be made therein which are within the full intended scope of this invention, as defined by the appended claims.

I claim:

5. In a vehicle lift having a vehicle supporting structure including a pair of transversely spaced longitudinally extended frame members, vehicle-engaging devices for said frame members including base members movably carried on said frame members for movement longitudinally thereof, coacting means on said frame members and said base members for locking said base members against tilting movement relative to said frame members at any moved position of said base members, horizontal arm members rotatably supported at one end on said base members, with the lower sides of the arm members, at the one end thereof, being adapted for bearing engagement with the upper sides of said base members in all moved positions of said arm members, and upright members at the free ends of said arm members adapted to engage portions of the chassis of a vehicle to be lifted.

2. In a vehicle lift having a vehicle supporting structure including a pair of transversely spaced longitudinally extended frame members, vehicle engaging devices for said frame members including base members movably supported on the upper sides of said frame members for movement longitudinally thereof, horizontal arm members rotatably supported at one end on said base members at positions substantially centered between the lateral sides of said frame members to provide for the movement of the free ends of said arms to positions spaced outwardly from either side of said frame members, means supporting said arms against up and down tilting movement at all moved positions thereof, and upright vehicle engaging members at the free ends of said arms.

3. In a vehicle lift including a vehicle supporting structure having a pair of transversely spaced longitudinally extended frame members, vehicle engaging devices including base members slidably supported on the upper sides of said frame members for movement longitudinally thereof, coacting means on said base members and frame members for locking said base members against tilting movement relative to said frame members in all moved positions of said base members, flat bearing portions on the top sides of said base members, shafts on said base members extended upwardly from said bearing portions, horizontal arms rotatably supported at one end on said upright shafts, with the lower sides of the one end of said arms being constructed for bearing engagement with said bearing portions, and upright members on said arms spaced from said upright shafts and adapted to engage portions of the chassis of a vehicle to be elevated.

GEORGE FREY.
